CLAIM

The ornamental design for keyed electrical connector assembly, as shown and described.

DESCRIPTION

FIG. 1 is a front perspective view of a keyed electrical connector assembly showing my new design;

FIG. 2 is a rear perspective view thereof;

FIG. 3 is a top view thereof;

FIG. 4 is a side view thereof;

FIG. 5 is a bottom view thereof;

FIG. 6 is a front view of a first portion of the keyed electrical connector assembly; and,

FIG. 7 is a front view of a second portion of the keyed electrical connector assembly.

The broken line portion of the figure drawings is included to show unclaimed subject matter only and forms no part of the claimed design.
